UNITED STATES PATENT OFFICE.

WILLIAM BUTLER ROBINSON, OF NEW YORK, N. Y.

CLOTHES-LINE SUPPORT.

SPECIFICATION forming part of Letters Patent No. 643,160, dated February 13, 1900.

Application filed August 31, 1899. Serial No. 729,051. (No model.)

To all whom it may concern:

Be it known that I, WILLIAM BUTLER ROBINSON, a citizen of the United States, residing at New York, in the county of New York and 5 State of New York, have invented certain new and useful Improvements in Clothes-Line Supports, of which the following is a full and complete specification, such as will enable those skilled in the art to which it appertains to make and use the same.

This invention relates to clothes-line supports, and has more particular relation to a device of this class which may be pivoted within a window-frame or in connection with 15 any suitable support where it may be normally retained in depressed position and may be swung into operative horizontal or projected position when desired.

My invention is fully disclosed in the following specification, of which the accompanying drawing forms a part, and in which is shown a clothes-line support constructed according to my invention and pivotally mounted in connection with the wall of a building 25 and within the window-opening in said wall, as shown in the drawing.

Referring more particularly to the drawing, I have shown at *a* an inner view of a portion of the wall of a window-opening composed of brick, wood, or other ordinary material, and connected therewith is a supporting-plate *b*, in which is fixed a stub-shaft *c*, and pivotally mounted upon said stub-shaft is a supporting-arm *d*. The supporting-arm *d* is pivoted adjacent the inner end portion, 35 which is curved beyond the pivotal point, as at *e*.

Journaled upon the stub-shaft *c*, exterior of the arm *d*, is a pulley *f*, and journaled 40 upon a stub-shaft *g*, projecting from the end of the curved end portion *e* of the arm *d*, is a pulley *h*. The outer end portion of the arm *d* is inwardly deflected, as at *j*, and between said deflected outer end and the arm *d* proper is supported a short shaft *k*, upon 45 which is journaled a pulley *l*.

The clothes-line *m* is passed about all the pulleys named, passing above the pulley *h*, about the pulley *l*, and above the pulley *f*, 50 and if the said clothes-line be continuous or of sufficient length clothes may be secured thereto and the clothes-line operated about

said pulleys to advance said clothes toward the outer end of the arm *d* and to withdraw them from such position. In this operation 55 the clothes are connected with the lower strand of the line *m*, and the upper strand of the latter is grasped above the pulley *f* and moved inwardly to draw the clothes out from the building, and the lower strand is drawn 60 inwardly to draw the clothes in toward the building. This manipulation of the clothes-lines is expedited by the upwardly-curved portion *e* of the arm *d*, the pulley *h* holding the line *m* clear of the pulley *f*. The holding or supporting strand of the line is supported by the pulleys *l* and *f*, and the upper strand is supported by the pulleys *l* and *h*. Thus despite the weight of the load upon 65 the lower strand the upper strand is always 70 within reach for manipulating the line.

In the drawing the arm *d* is shown extended horizontally or at right angles to the face *n* of the building, having the window-opening *a*, and this position is the operative position of 75 the device. The arm *d* is retained in this horizontal position by any desired means— as, for instance, by properly securing the line *m* within the window-opening or inside 80 the window.

A stop *o* is arranged adjacent the plate *b* and serves to prevent extreme upward movement of the arm *d*. A stop or catch *p* is arranged at a predetermined point beneath the plate *b*, and the arm *d*, when not in use, may 85 be swung downwardly and secured to the catch *p* in inoperative position.

It is evident that many changes may be made in the construction and arrangement of the clothes-line support described without 90 departing from the spirit of my invention.

Having fully described my invention, I claim as new and desire to secure by Letters Patent—

The herein-described clothes-line support, 95 comprising a single arm which is pivotally mounted adjacent one end, which end is curved upwardly and provided with a pulley, said arm being also provided at its outer end with a pulley and intermediate of said ends 100 with a pulley, the relative construction and arrangement being such that a line passed above said pulley connected with said curved end about said pulley connected with the

other end, and thence above said intermediate pulley will form when tautened an upper and a lower strand, the upper of which may readily be manipulated to operate the lower of which, substantially as shown and described.

In testimony that I claim the foregoing as

my invention I have signed my name, in presence of the subscribing witnesses, this 1st day of August, 1899.

WILLIAM BUTLER ROBINSON.
